A. E. ANDERSON

AUTOMATIC SWITCHING SYSTEM

Filed April 28, 1927

Inventor:
Arvid E. Anderson,
by Myron S. Fink
His Attorney.

UNITED STATES PATENT OFFICE.

ARVID E. ANDERSON, OF SCOTIA, NEW YORK, ASSIGNOR TO GENERAL ELECTRIC COMPANY, A CORPORATION OF NEW YORK.

AUTOMATIC SWITCHING SYSTEM.

Application filed April 28, 1927. Serial No. 187,402.

5 My invention relates to automatic switching systems, and particularly to switching systems for selectively controlling the connections between a load circuit and two alternating current sources and its object is to provide an improved switching system of this particular kind.

10 In systems of distribution in which a load circuit is normally supplied by a preferred source of current when the conditions of that source are normal, and an emergency source of current is arranged to supply current to the load circuit when the preferred source fails, it is desirable to reconnect the preferred source, when it is reenergized, to the load circuit before the emergency source is disconnected therefrom in order that the supply of current to the load circuit may not be interrupted when the transfer is made. In 15 accordance with one feature of my invention I provide an arrangement whereby the preferred source, when reenergized while the emergency source is supplying current to the load circuit, is not reconnected to the load circuit until a predetermined phase relation occurs between the voltages of the two sources so that when the two sources are connected together an excessive circulating current does not flow between the two sources.

20 My invention will be better understood from the following description taken in connection with the accompanying drawing and its scope will be pointed out in the appended claims.

25 Referring to the accompanying drawing, which is a diagram of an automatic switching system for selectively controlling the connections between a load circuit, a preferred source of current and an emergency source of current, 1 and 2 represent two sources of current, shown as supply circuits, which are adapted to be connected to a load circuit 3 by the circuit breakers 4 and 5 respectively which may be of any suitable type, examples 30 of which are well known in the art. As shown the circuit breakers 4 and 5 are of the well known latched-in type and are provided with the closing coils 6 and 7 respectively and the trip coils 8 and 9 respectively.

35 10 and 11 are voltage relays which are adapted to be energized from the preferred and the emergency sources respectively. The voltage relay 10 has a control relay 12 associated therewith which is arranged to be energized when the voltage relay 10 is ener-

gized a predetermined amount. The voltage relay 11 has a similar control relay 13 which however is only energized when the voltage relay 11 is energized a predetermined amount and the voltage relay 10 is deenergized. The 60 control relays 12 and 13 are preferably time-delay relays so that they do not function until after their coils have been energized a certain length of time. In this manner momentary changes in the voltages of the 65 sources do not effect unnecessary openings and closings of the circuit breakers.

65 In order that either source may be employed as the preferred source a change-over switch 15 is provided which is adapted when 70 moved to different positions to change the connections of the various control devices to accomplish this result. When the change-over switch 15 is in its left-hand position the source 2 is the preferred source and source 75 1 is the emergency source, and when the change-over 15 is in its right-hand position the source 1 is the preferred source and the source 2 is the emergency source.

70 In order to effect the closing of the circuit breaker associated with the preferred source when it is reenergized, I provide an automatic synchronizing device 16 which is arranged to operate to effect the closing of the preferred circuit breaker when a predetermined phase relation occurs between the voltages of the two sources 1 and 2. This synchronizing device may be of any suitable type, examples of which are well known in the art. If the sources 1 and 2 are connected 80 together at some other point so that their frequencies are the same but the phases of their voltages at the points where they are connected to the load circuit may differ from each other, it is preferable to have the synchronizing device 16 arranged so that it closes its contacts 17 only when the phase difference remains less than a certain amount for more than a predetermined length of time. If the sources 1 and 2 are 90 independent sources so that they may differ in frequencies as well as phase it is preferable in that case to use a synchronizing device which also functions in accordance with the frequency difference. Such a device is 100 shown in Letters Patent Reissue 16,540 to O. C. Traver. Since the particular construction of the synchronizing device forms no part of my invention I have not shown the device in detail.

In order to effect the reclosing of the circuit breaker associated with the preferred source in case it is reenergized and the automatic synchronizing device 16 fails to function within a predetermined time I provide a time relay 18 which is arranged to effect first the opening of the circuit breaker associated with the emergency source and then the closing of the circuit breaker associated with the preferred source.

19 and 20 are control relays of the well known hesitating type which control the circuits of the closing coils 6 and 7 respectively. 21 and 22 are control transformers which are connected respectively to the sources 1 and 2 and which supply current to the various control devices.

Since it is usually desirable to have any tripping action due to over-current transferred to the generating station breaker, the circuit breakers 4 and 5 are preferably provided with over-current protection which functions only in case of a very severe over-load which warrants the locking out of the circuit breakers. In the drawing I have shown an overload relay 23 which is connected to the load circuit 3 by a current transformer 24. The overload relay 23 controls the circuit of a lock-out relay 26 which is arranged in any suitable manner, examples of which are well known in the art so that it remains in its energized position after its coil is deenergized until it is reset by hand. The coil of the lock-out relay 26 is arranged to be connected in series with the trip coil 8 and contacts 27 of relay 23 if the circuit breaker 4 is closed when the overload relay 23 is operated and to be connected in series with the trip coil 9 and contacts 28 of relay 23 if the circuit breaker 5 is closed when the overload relay 23 is operated. The lock-out relay 26 when in its energized position prevents the circuit of both closing coils from being completed.

45 The operation of the system shown is as follows:—It will be assumed that the change-over switch 15 is in its left-hand position, that both of the circuit breakers 4 and 5 are open, and that both of the sources 1 and 2 are energized simultaneously. The relay 10 is connected across the secondary of the transformer 22 by contacts 33 and 34 of the change-over switch 15 so that the relay is energized by the voltage of the preferred source 2. By closing its contacts 35, the relay 10 completes the circuit of the coil of the time-relay 12 across the secondary of the transformer 22 through contacts 33 and 34 of the change-over switch 15. The relay 11 is connected across the secondary of the transformer 21 by contacts 36 and 37 of the change-over switch so that the relay is energized by the emergency source 1. By closing its contacts 38 the relay 11 closes contacts in the circuit of the time-relay 13 but the circuit of this time-relay is

open at this time at the contacts 39 of the relay 10. Therefore only the time relay 12 is energized long enough to close its contacts when both sources are simultaneously energized.

70 The coils 40 and 41 of the synchronizing device 16 are also connected across the secondaries of the transformer 22 and 21 respectively by the contacts 33, 34, and 36, 37 so that the synchronizing device is operative to close its contacts 17 when the predetermined phase relation between the voltages of the two sources occurs. Preferably the time delay of the synchronizing device 16 is longer than the time delay of relays 12 so that it does not have time to close its contacts 17 before the preferred circuit breaker is closed.

75 After a predetermined time, relay 12 closes its contacts 42 thereby completing a circuit for the hesitating control relay 20 to effect 80 the completion of the circuit of the closing coil 7. The circuit of the control relay 20 is from one side of a suitable source of control current through the auxiliary contacts 43 on circuit breaker 5, coil 20, conductor 44, contacts 45 of lockout relay 26, conductor 46, auxiliary contacts 47 on circuit breaker 4, conductor 48, contacts 49 and 50 of change-over switch 15, conductor 51, contacts 42 of relay 12 to the other side of the control source. The control relay 20 by closing its contacts 52 completes the circuit of the closing coil 7 so that the circuit breaker 5 closes and connects the preferred source 2 to the load circuit 3.

85 It will now be assumed that while the circuit breaker 5 is closed and the emergency source 1 is energized the source 2 fails so that the voltage relay 10 opens its contacts 35, which causes the time relay 12 to be deenergized, and closes its contacts 39 so that the coil of the time-relay 13 is connected across the secondary of the transformer 21.

90 After the coil of the relay 13 has been energized for a predetermined length of time, the relay 13 closes its contacts 54 and completes a circuit for the trip coil 9 so that the circuit breaker 5 opens and disconnects the source 2 from the load circuit 3. The circuit of the trip coil 9 is from one side of a suitable source of control current through auxiliary contacts 55 on the circuit breaker 5, trip coil 9, conductor 56, contacts 57 and 58 of change-over switch 15, conductor 59, contacts 54 of relay 13 to the other side of the source of control current. As soon as the circuit breaker 5 opens a circuit is completed for the hesitating control relay 19 to effect the closing of the circuit breaker 4. The circuit for the relay 19 is from one side 105 of a suitable source of control current through auxiliary contacts 60 on circuit breaker 4, coil of relay 19, conductor 61, contacts 62 of lock-out relay 26, conductor 63, auxiliary contacts 64 on circuit breaker 5, conductor 65, contacts 110

66 and 67 of change-over switch 15, conductor 59, contacts 54 of relay 13 to the other side of the source of control current. The relay 19 by closing its contacts 68 completes the circuit of the closing coil 6 so that the circuit breaker 4 closes and connects the source 1 to the load circuit 3.

It will be assumed now that while the emergency source 1 is supplying current to the load circuit 3 the voltage conditions of the preferred source are restored to normal so that the relays 10 and 12 are reenergized in the manner heretofore described and the time relay 13 is deenergized by the relay 10 opening its contacts 39. The time relay 12 when it closes its contacts 42 does not complete the heretofore described circuit for the hesitating control relay 20 because this circuit is now open at the auxiliary contacts 47 on the circuit breaker 4. When however the predetermined phase relation exists between the voltages of the two sources 1 and 2 so that the synchronizing relay 16 closes its contacts 17, a circuit is completed for the hesitating control relay 20. This circuit is from one side of a suitable source of control current, through auxiliary contacts 43 on the circuit breaker 5, coil of relay 20, conductor 44, contacts 45 of lock-out relay 26, conductor 46, contacts 69 and 70 of change-over switch 15, conductor 71, contacts 17 of synchronizing device 16, conductor 51, contacts 42 of relay 12 to the other side of the control source. The energization of the hesitating control relay 20 effects the closing of the circuit breaker 5 in the manner heretofore described. The preferred source 2 therefore is reconnected to the load circuit 3 before the emergency source 1 is disconnected therefrom. When the circuit breaker 5 closes a circuit is completed for the trip coil 8 of the circuit breaker 4 to effect the opening of this circuit breaker and the disconnection of the emergency source 1 from the load circuit 3. The circuit of the trip coil 8 is from one side of a suitable source of control current through auxiliary contacts 72 on the circuit breaker 4, trip coil 8, conductor 73, contacts 74 and 75 of change-over switch 15, conductor 76, auxiliary contacts 77 on circuit breaker 4, conductor 78, auxiliary contacts 79 on circuit breaker 5, conductor 51, contacts 42 of relay 12 to the other side of the control source.

If for any reason the desired phase relation between the voltages of the two sources does not occur within a predetermined time after the preferred source is reenergized the time relay 18, which has a relatively long time delay, operates to effect the opening of the circuit breaker associated with the emergency source and the subsequent closing of the circuit breaker associated with the preferred source. The circuit of the time-relay 18 is completed when the preferred circuit breaker is open and the contacts 80 of the re-

lay 12 are closed. This circuit is from one side of a suitable source of control current through auxiliary contacts 43 on the circuit breaker 5, conductor 81, contacts 82 and 83 of change-over switch 15, conductor 84, coil of relay 18, contact 80 of relay 12 to the other side of the control source. Relay 18 by closing its contacts 85 completes a circuit for the trip coil 8 of the circuit breaker 4 to effect the opening of the circuit breaker. This circuit is from one side of a suitable source of control current through auxiliary contacts 72 on circuit breaker 4, trip coil 8, conductor 73, contacts 74 and 75 of change-over switch 15, conductor 76, contacts 85 of relay 18, conductor 51, contacts 42 of relay 12 to the other side of the control source. The circuit breaker 4 by closing its contacts 47 when it opens completes the heretofore described circuit for the hesitating control relay 20 to effect the closing of the circuit breaker 5.

If the circuit breaker 4 should be closed at any time when the emergency source 1 is de-energized and the preferred source 2 is energized a circuit is completed for the trip coil 8 as soon as the relay 12 closes its contacts 42. This circuit is from one side of a suitable source of control current through auxiliary contacts 72 on circuit breaker 4, trip coil 8, conductor 73, contacts 74 and 75 of change-over switch 15, conductor 76, contacts 86 of voltage relay 11, conductor 51, contacts 42 of relay 12 to the other side of the control source. The closing of the circuit breaker 5 is then effected by the relay 20 the circuit of which is completed by the circuit breaker 4 closing its auxiliary contacts 47, as heretofore described.

If at any time an excessive overload occurs on the load circuit 3 so that the overload relay 23 is sufficiently energized to close its contacts 27 and 28, a circuit is completed for the trip coil of whichever circuit breaker is closed and the coil of the lockout relay 26. The lockout relay 26 by opening its contacts 45 and 62 prevents any further automatic closing of the circuit breakers until the relay 26 is reset by hand.

If it is desired to have the source 1 as the preferred source, the change-over switch 15 is placed in its right-hand position. The voltage relay 10 and its associate time-relay 12 are then connected across the secondary of the transformer 21 by contacts 36 and 87 of the change-over switch and the voltage relay 11 and its associate time-relay 13 are connected across the secondary of the transformer 22 by contacts 33 and 37 of the change-over switch. The conductor 59 is connected to the conductors 73 and 48 by contacts 58 and 88 and contacts 67 and 49 respectively of the change-over switch so that time-relay 13 controls the circuit of the trip coil 8 of the circuit breaker 4 associated with the source 1 which is now the preferred source and the circuit of the hesitating control relay 20 of the

emergency circuit breaker 5. The conductor 71 is connected to conductor 63 by contacts 70 and 90 of the change-over switch so that synchronizing relay 16 controls the circuit of 5 hesitating control relay 19 associated with the preferred source 1. The conductor 76 is connected to the conductor 56 by contacts 75 and 91 of the change-over switch so that trip coil 9 associated with the emergency breaker 5 is 10 controlled by the time-relay 18 and the voltage relay 11, and the conductor 84 is connected to the auxiliary contacts 60 on the circuit breaker 4 by contacts 83 and 92 on the change-over switch so that the time-relay 18 15 is energized whenever the preferred circuit breaker 4 is open and the contacts 80 of the time-relay 12 are closed.

Since the operation of the system when the change-over switch 15 is in its right-hand 20 position is similar to the heretofore described operation when it is in its left-hand position, it will be obvious to one skilled in the art and therefore it is believed that a detail description is unnecessary.

25 While I have in accordance with the Patent Statutes shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

What I claim as new and desire to secure 30 by Letters Patent of the United States, is:—

35 1. In combination, a load circuit, a source of current connected thereto, another source of current normally disconnected from said load circuit, means responsive to a predetermined abnormal condition of said first mentioned source for effecting the disconnection thereof from said load circuit and the connection of said other source to said load circuit, and means responsive to a predetermined phase relation between the voltages of said sources when said other source is connected to said load circuit for effecting the reconnection of said first mentioned source to said load circuit.

40 2. In combination, a load circuit, a source of current connected thereto, another source of current normally disconnected from said load circuit, means responsive to a predetermined abnormal condition of said first mentioned source for effecting the disconnection thereof from said load circuit, and the connection of said other source to said load circuit, and means responsive to a predetermined phase relation between the voltage of said sources when said other source is connected to said load circuit for effecting the reconnection of said first mentioned source to said load circuit and the subsequent disconnection of the other source from said load circuit.

45 3. In combination, a load circuit, a pre-

ferred source of current, switching means for connecting said preferred source to said load circuit, an emergency source of current, a second switching means for connecting said emergency source to said load circuit, means 50 responsive to a predetermined abnormal condition of said preferred source for effecting the opening of said first mentioned switching means, means responsive to the opening of said first mentioned switching means for 55 effecting the closing of said second switching means, and means responsive to a predetermined phase relation between the voltages of said sources when said second switching means is closed and both of said sources are 60 energized for reclosing said first mentioned switching means.

4. In combination, a load circuit, a preferred source of current, switching means for connecting said preferred source to said load circuit, an emergency source of current, a second switching means for connecting said emergency source to said load circuit, means responsive to a predetermined abnormal voltage condition of said preferred source when the voltage conditions of said emergency source are normal for effecting the opening of said first mentioned switching means and the closing of said second switching means, and means responsive to a predetermined abnormal voltage condition of said preferred source when the voltage conditions of said emergency source are normal for effecting the opening of said first mentioned switching means and the closing of said second switching means.

5. In combination, a load circuit, a preferred source of current, switching means for connecting said preferred source to said load circuit, an emergency source of current, a second switching means for connecting said emergency source to said load circuit, means responsive to a predetermined abnormal voltage condition of said preferred source when the voltage conditions of said emergency source are normal for effecting the opening of said first mentioned switching means, means responsive to the opening of said first mentioned switching means for effecting the closing of said second switching means, means responsive to a predetermined phase relation between the voltages of said sources when said second switching means is closed for reclosing said first mentioned switching means, and means responsive to the reclosing of said first mentioned switching means for effecting the opening of the second switching means.

6. In combination, a load circuit, a source of current connected thereto, another source of current normally disconnected from said load circuit, means responsive to a predetermined abnormal voltage condition of said first mentioned source for effecting the disconnection thereof from said load circuit and the connection of said other source to said load circuit.

- load circuit, synchronizing means responsive to a predetermined phase relation between the voltages of said sources after the voltage conditions of said first mentioned source are 65
 5 restored to normal for effecting the reconnection of said first mentioned source to said load circuit, and means for effecting the disconnection of said other source from said load circuit and the subsequent reconnection of said 70
 10 first mentioned source to said load circuit when said synchronizing means fails to effect the reconnection of said first mentioned source within a predetermined time after the voltage conditions thereof are restored to 75
 15 normal.
7. In combination, a load circuit, a source of current connected thereto, another source of current normally disconnected from said load circuit, means responsive to a predetermined abnormal voltage condition of said first mentioned source for effecting the disconnection thereof from said load circuit and the connection of said other source to said 80
 20 load circuit, synchronizing means responsive to a predetermined phase relation between the voltages of said sources after the voltage conditions of said first mentioned source are restored to normal for effecting the reconnection of said first mentioned source to said 85
 25 load circuit, synchronizing means responsive to a predetermined phase relation between the voltages of said sources after the voltage conditions of said first mentioned source are restored to normal for effecting the reconnection of said first mentioned source to said 90
 30 load circuit and the subsequent disconnection of said other source from said load circuit, and means for effecting the disconnection of said other source from said load circuit and the subsequent reconnection of said first mentioned source to said 95
 35 load circuit when said synchronizing means fails to effect the reconnection of said first mentioned source within a predetermined time after the voltage conditions thereof are restored to normal. 100
 40 8. In combination, a load circuit, a source of current connected thereto, another source of current normally disconnected from said load circuit, means responsive to a predetermined abnormal voltage condition of said first mentioned source for effecting the disconnection thereof from said load circuit and the connection of said other source to said load circuit, synchronizing means responsive to a predetermined phase relation between the voltages of said sources after the voltage conditions of said first mentioned source are restored to normal for effecting the reconnection of said first mentioned source to said load circuit, and means for effecting the disconnection of said other source from said load circuit and the subsequent reconnection of said first mentioned source to said load circuit when the voltage condition of said other source becomes abnormal while supplying current to said load circuit and the voltage conditions of said first mentioned source are subsequently restored to normal. 110
 45
 50
 55
 60
9. In combination, a load circuit, a source of current connected thereto, another source of current normally disconnected from said load circuit, means responsive to a predetermined abnormal voltage condition of said first mentioned source for effecting the disconnection thereof from said load circuit, synchronizing means responsive to a predetermined phase relation between the voltages of said sources after the voltage conditions of said first mentioned source are restored to normal for effecting the reconnection of said first mentioned source to said load circuit, and means for effecting the disconnection of said other source from said load circuit and the subsequent reconnection of said first mentioned source to said load circuit when the voltage condition of said other source becomes abnormal while supplying current to said load circuit and the voltage conditions of said first mentioned source are subsequently restored to normal.
10. In combination, a load circuit, a plurality of sources of current adapted to supply current to said circuit, means for selecting different sources as the preferred source, means responsive to a predetermined abnormal condition of the selected source for effecting the disconnection thereof from the said load circuit when it is being supplied thereby and the connection of another of said sources to said load circuit, and means responsive to a predetermined phase relation between the voltages of said selected source and said other source when said other source is connected to said load circuit for effecting the reconnection of said first-mentioned source to said load circuit. 105
11. In combination, a load circuit, two sources of current for said load circuit, means for selecting either of said sources as the preferred source, voltage responsive means controlled by said selecting means so that it is responsive to which ever source is the preferred source, means controlled by said voltage responsive means for effecting the disconnection of the preferred source from the load circuit and the connection of said other source to said load circuit when said preferred source is supplying current to said load circuit and a predetermined abnormal voltage condition occurs on said preferred source, and means responsive to a predetermined phase relation between the voltages of said sources when said other source is connected to said load circuit for effecting the reconnection of said first-mentioned source to said load circuit and the subsequent disconnection of said other source from said load circuit. 115
- In witness whereof, I have hereunto set my hand this 27th day of April, 1927.
- ARVID E. ANDERSON.
